UNITED STATES PATENT OFFICE

LOREN L. HOPKINS, OF WEST NEW YORK, NEW JERSEY

SANDING DEVICE FOR VEHICLES

Application filed March 18, 1929. Serial No. 347,798.

This invention is an improvement in certain of the features of construction of the invention broadly claimed in my prior and co-pending application Serial No. 278,381, filed 5 May 17, 1928. In my prior construction as well as in the present one there is provided a sand container which is connected by a conduit to a nozzle located adjacent to one of the wheels of the vehicle and having means 10 for opening and closing the nozzle whereby the delivery of sand to the tire or in the path of the wheel may be controlled at will.

One object of my present invention is to facilitate the delivery of the sand from the 15 container to the nozzle and provide a more direct path for the sand. To accomplish this result I mount the nozzle in a substantially vertical position so that the sand may flow from the container to the nozzle and 20 through the latter in an approximately straight line and without sharp angle bends which retard the flow.

A further object of the invention is to better insure the loosening of the sand in the 25 nozzle at the time the latter is opened so that in case the sand has become caked it will be jarred loose and the flow started. To accomplish this result I mount the nozzle in such a way that it is given a bodily movement at the same time that the nozzle is 30 opened. If this movement be comparatively rapid, as would ordinarily be the case, the resulting jar or shaking of the sand in the nozzle will tend to break up any caking in 35 case any should have occurred during a long period of non-use.

A further object of my invention is to better insure the closing of the nozzle so that the nozzle cannot be kept open by particles 40 of sand, and thus leakage of the sand from the nozzle when the latter is supposed to be closed, is thereby prevented. To accomplish this result I provide a closure member which instead of being hinged is free floating 45 and automatically seating.

A further object of the invention is to prevent the entry into the nozzle of any water which may spatter up from the ground or be thrown onto the nozzle by the adjacent 50 wheel or which may drip from the underside

of the body of the vehicle. I accomplish this result by providing the nozzle with an annular groove or recess in the delivery end and encircling the delivery outlet so that any water striking the outside of the nozzle 55 will drip therefrom without contacting with the closure or the edge of the outlet opening.

In the accompanying drawings I have illustrated merely one embodiment of my invention. 60

In these drawings:

Fig. 1 is a side elevation of the apparatus, certain of the parts being shown in section and a portion of the vehicle being indicated somewhat diagrammatically; 65

Fig. 2 is a transverse section on the line 2-2 of Fig. 1; and

Fig. 3 is a central longitudinal section through the delivery nozzle.

In the construction illustrated there is provided a sand container 10 which is preferably formed of flexible waterproof material and sealed against the admission of air or moisture. By making the container flexible it may collapse as sand is delivered therefrom 70 and without an admission of moist air to the container. Thus when the container is filled with dry sand the sand will remain dry until used. 75

The container is preferably mounted with- 80 in the body of the vehicle, and at a point approximately above and in front of the wheel adjacent to which the sand is to be delivered.

The container when ready for use stands in 85 an upright position and is detachably connected to a delivery conduit 11 which may extend through the floor of the vehicle body. The coupling illustrated is substantially the same as that shown in my prior application 90 and includes a hollow threaded boss 12 on the container adapted to enter a union 13 on the end of the conduit. A cap may be screwed onto the boss to seal the container from the time the container is filled until it is connected 95 to the conduit for use. Within the coupling may be employed a plate 14 with an aperture therein of a size to regulate the flow of sand. This coupling may be mounted in a floor A 100 of the vehicle body.

The conduit at its lower end is secured to a delivery nozzle 15 which is preferably mounted below the running board B and adjacent to the rear wheel C. As the device is intended to deliver sand for preventing lateral skidding as well as to give better traction, the nozzle is preferably mounted at one side of the medial plane of the wheel so that it will deliver most of the sand against or in the path of the tread at one side of the center of the latter.

In my improved construction this nozzle 15 extends in a substantially vertical position and is pivotally supported on a cross arm 16 rigidly secured to a bracket 17 which latter may be secured to the underside of the running board. The upper end of the nozzle is connected by a wire or other flexible member 18 to a point adjacent the driver whereby upon operating a suitable lever, pedal or the like, the member 18 may be pulled to swing the latter end of the nozzle toward the wheel.

The nozzle 15 is preferably rectangular in cross-section and has a bottom wall 19 which has a large sand outlet opening 20. The bottom wall 19 is mounted above the lower end of the side walls of the nozzle and has a depending flange 21 encircling the opening 20 so that there is an annular groove or recess 22 open at its lower end and between the outlet 20 and the peripheral wall. Any water which strikes the nozzle and trickles down the sides will thus drop from the side walls and cannot flow across to the closure or the wall of the opening 20. The closure is in the form of a plate 23 somewhat larger than the opening 20 and smaller than the peripheral wall 15 so that it may lie against the edge of the depending flange 21 and with its peripheral edge in the annular recess 22. This closure 23 is not hinged or otherwise directly connected to the nozzle, but is held in place by a coil spring 24 extending lengthwise of the nozzle within the latter and diagonally from the upper end of the nozzle to the closure adjacent to one edge of the latter. This same edge portion of the closure is connected by a V-shaped link having a transverse portion 25 journaled in the closure and a pair of side arms 26 extending along the outer side of the nozzle lengthwise of the latter to extensions 27 on the cross arm 16. The upper ends of the links 26 are thus stationary while the lower ends are laterally movable as the nozzle swings upon the cross arm 16 as a stationary pivotal support.

In Fig. 3 I have shown the device in solid lines in normally closed position and have shown in dotted lines the position of the parts after the nozzle has been swung for a short distance toward the wheel. It will be noted that during this swinging movement of the nozzle the links 26 force the closure open against the action of the spring 24. I have shown the nozzle swung to only a short dis-

tance, but it will be evident that in practice the further the nozzle is swung the wider will the closure open. Through the swinging movement which opens the closure the sand within the nozzle is jarred or shaken and at the same time the sand is agitated by the stretching of the spring 24 and by the lateral movement of the spring due to the swinging of the closure. Thus in case the sand has become caked it will be loosened to flow freely from the nozzle.

As the spring 24 is connected to the same side of the closure as are the links 26 the opening movement of the closure will be substantially the same as though the opposite edge of the closure were hinged to the nozzle, but preferably no hinge is employed. If no hinge is employed, the closure, when it returns to closed position, will automatically seat and prevent further escape of sand. This would not be the case if the closure were hinged because a few grains of sand might catch between the closure and its seat adjacent to the hinge. A very small amount of sand at this point might hold the opposite edge of the closure open a short distance which would permit continuous loss of sand, whereas by omitting the hinge no part of the closure will be opened to a greater extent than the thickness of a grain of sand, and leakage will be entirely prevented.

It will be obvious that the construction illustrated in the drawing is one embodiment of my invention and that various other forms and constructions might be designed within the scope of the appended claims and without departing from the spirit of my invention. Likewise the features of construction hereinafter claimed might be used in systems other than that disclosed in my prior application above referred to.

The device illustrated is for applying sand to only a single wheel. It will be obvious that the same construction might be duplicated for each of the four wheels of the vehicle, and it will also be obvious that two or more of the nozzles illustrated may be connected so as to draw sand from the single container or other source of supply.

Having thus described my invention, what I claim as new and desire to secure by Letters Patent is:

1. A sanding device for vehicles including a nozzle having a closure, a spring within the nozzle for normally holding the closure in closed position, means for swinging the nozzle, and means for automatically opening the closure against the action of said spring during said swinging movement.

2. A sanding device for vehicle wheels, including a substantially vertically disposed nozzle, a pivotal support therefor at one side of the nozzle and adjacent to the upper end, said nozzle having an arm extending laterally along one side thereof, a closure for the lower

end of the nozzle, a connection between said closure and the extremity of said arm for opening the closure during the swinging of the nozzle on its support, and a spring within the nozzle for normally holding the closure in closed position and also normally holding the nozzle against swinging movement.

3. A sanding device for vehicle wheels including a pivoted nozzle, a pivoted closure for the end of the nozzle, and a spring for resisting swinging movement of the nozzle and opening movement of the closure, said spring being disposed within the nozzle and extending approximately lengthwise thereof.

4. A sanding device for vehicle wheels including a nozzle disposed in approximately vertical position, means for delivering sand to the upper end thereof, and a closure for the lower end thereof, said lower end having an annular recess encircling the outlet opening and within the peripheral wall of the nozzle.

5. A sanding device for vehicle wheels including a nozzle disposed in a substantially vertical position and having a bottom wall within and above the lower end of the peripheral wall and provided with an outlet opening encircled by a depending flange, whereby an annular recess is formed around the outlet opening, and a closure for said opening.

6. A sanding device for vehicle wheels including a nozzle disposed in a substantially vertical position and having a bottom wall within and above the lower end of the peripheral wall and provided with an outlet opening encircled by a depending flange, whereby an annular recess is formed around the outlet opening, and a closure for said opening, said closure being disposed above the peripheral wall of the nozzle and with its peripheral edge in said recess.

7. A sanding device for vehicle wheels including a nozzle disposed in a substantially vertical position and having a peripheral wall and a bottom wall, said bottom wall being disposed above and within the lower end of the peripheral wall and provided with an outlet opening and a depending flange encircling said opening, and a closure above the lower edge of the peripheral wall and seating against the lower end of said flange.

8. A sanding device for vehicle wheels including a nozzle disposed in a substantially vertical position and having a peripheral wall and a bottom wall, said bottom wall being disposed above and within the lower end of the peripheral wall and provided with an outlet opening and a depending flange encircling said opening, a closure above the lower edge of the peripheral wall and seating against the lower end of said flange, and a spring within said nozzle and connected to said closure to serve as the sole means for connecting the closure to the nozzle, whereby the closure may seat at any edge of the outlet opening irre-

spective of its seating position at other edges of the opening.

Signed at New York, in the county of New York and State of New York, this 14th day of March A. D. 1929.
